HOLDER FOR BOOK MATCHES OR THE LIKE

John H. Eskew, 3410A Park, St. Louis, Mo. 63104

Filed Apr. 7, 1966, Ser. No. 1,806

Term of patent 3½ years

(Cl. D85—2)

FIG. 1.

FIG. 2.

FIG. 3.

FIG. 1 is a perspective of a holder for book matches or the like showing my new design;

FIG. 2 is a side view of the FIG. 1 holder; and

FIG. 3 is a view from the left end of FIG. 2.

The essential features of the design are shown in full lines on the drawing.

I claim:

The ornamental design for a holder for book matches or the like, substantially as shown and described.
